UNITED STATES PATENT OFFICE

EDWARD CHESHIRE, OF ST. PETERSBURG, FLORIDA

SHEET REGISTER DEVICE

Application filed June 29, 1925. Serial No. 40,259.

My invention pertains to sheet feeding and registering devices. In the ordinary automatic feeding of sheets to platen printing presses, it is usual to provide a separate registering device which operates to bring the newly fed sheet to a final, correctly registered position on the platen, after the actual feeding operation has been performed. It is an object of my invention to overcome the necessity of such a separate device; and I attain this object by providing a mechanism which will perform both the operation of feeding the sheet to the platen and the operation of bringing the sheet to a correct end and side registered position.

I have described in the following specification, and shown by way of example in the accompanying drawings, one form of mechanism in which my invention may be embodied. However, it will be understood that the invention may be embodied in other forms, and that changes may be made in the form which I have described and shown, without exceeding the scope thereof, as defined in the appended claims.

In the drawings:

Fig. 1 is a side elevation of the mechanism, showing the feed grippers in their sheet receiving position;

Fig. 2 is a similar view to Fig. 1, but showing the feed grippers in the position they assume when about to deliver a sheet to the platen, and register it thereon;

Fig. 3 is a rear view of the mechanism;

Fig. 4 is an enlarged plan, the parts being shown in the position of Fig. 1;

Fig. 5 is a similar view to Fig. 4, but showing the parts in the position of Fig. 2;

Fig. 6 is an enlarged section taken on the line marked 6 in Fig. 2;

Fig. 7 is a section on the line 7—7 of Fig. 6, still further enlarged; and

Fig. 8 is an enlarged section on the line 8—8 of Fig. 3.

The feed mechanism herein disclosed is of the same broad type as that described in my co-pending application Ser. No. 732,443; filed August 16, 1924, for sheet feeding devices, but modified in construction so as to obtain

the desired result of performing the registering as well as the feeding function.

Referring now to the drawings, the main frame of the machine comprises a left-hand side casting 20 and a right-hand side casting 21, connected together so as to form a solid frame work for the support of the mechanism, and secured to the front horns of a Gordon press in the manner fully described in my co-pending application above referred to.

Located between the side castings 20 and 21 is an automatically elevated stock table 31, upon which is placed the pile of stock to be fed, the front of the pile engaging against a front plate 25. The top sheets are separated from the pile, and raised, one by one, into a position accessible for feeding, by means of pneumatic separator feet 41 secured to a vertically reciprocable separator bar 33. At each cycle of the machine, the separator bar 33 descends to bring the separator feet into contact with the front edge of the top sheet of the pile. Suction being thereupon applied, the top sheet becomes attached to the separator feet 41 and is carried up by the latter when the separator bar 33 rises again, thereby being brought into a position where its front edge can readily be seized by the feed grippers.

The side castings 20 and 21 are formed with bearings for receiving a rock shaft 47, the end of which extends outwardly of the left-hand side casting 20 and has secured to it the lower end of a feed-arm 48. At its front part, near the top, the feed-arm 48 is formed with a boss 49 in which is cut a slot 50. This slot is curved upon the arc of a circle, the center of which is on the axis of the pin which connects the left-hand crank arm *d* with the bed *e*, in the position which said pin assumes when the bed is in impression position. Secured in the slot 50 by a nut 51 is a pin 52, to which is rockably connected one end of a link 53. The other end of the link is connected with the press bed, in the manner fully described in my co-pending application above referred to. By this construction, the to and fro rocking of the bed effects a corresponding movement of the feed

arm 48, the latter swinging rearwardly away from the stock pile as the bed rocks rearwardly away from its impression position, and swinging forwardly towards the stock pile as the bed rocks forward to its impression position.

The feed arm 48 is formed at its top end with an elongated bearing 57 in which is rockably and slidably mounted a gripper-bar 58, the latter being rectangular in cross-section except for the part which enters the bearing 57. The feed grippers 59, two of which are provided, are mounted on the gripper-bar 58. Each gripper is formed with a channel-shaped central portion 60 adapted to fit on the square portion of the gripper-bar 58, and to be secured against removal therefrom by a plate 61 attached to the bottom of such central portion. A withdrawable spring-pressed pin 62 is mounted in the portion 60 and is adapted to enter one or another of a series of holes formed in the gripper-bar 58, thereby to permit the gripper as a whole to be adjusted longitudinally of the gripper-bar, to any desired position on the latter. Beyond the central portion 60, the gripper is of channel-shape in cross-section, so as to provide a pair of downward flanges 63, and is formed at its end with a cylindrical guide 64 for receiving the movable gripper-jaw 65, which latter is in the form of a cylindrical plunger adapted to close upon a fixed jaw 66 secured to the guide 64 so as to extend beneath the same. An actuating lever 67 is pivoted between the flanges 63 and is bowed at one end so as to extend over and beyond the central portion 60, at which end it is formed with a notch 68. At its opposite end, the actuating lever enters a recess 69 formed in the movable jaw 65, this recess being of such length as to permit lost motion between the jaw and the end of the lever. A leaf spring 67^a, carried by the gripper, presses downward upon the movable jaw 65 with a pressure which may be regulated by manipulating an adjusting screw 67^b.

During the cycle of the machine, by means which will be described below, the lever 67 is moved successively into three effective positions. In the first position, shown in Fig. 8, it presses upwardly on the top end of the recess 69, thereby raising the movable jaw 65. In this position the gripper is open, ready to receive a sheet. In the second position, it presses downwardly on the bottom end of the recess 69, thereby forcing the movable jaw 65 firmly down on a sheet interposed between it and the fixed jaw 66, whereby the sheet is gripped positively. In the third position, the movable jaw 65 is pressed by the action of the leaf spring 67^a alone against the sheet interposed between it and the fixed jaw 66, the end of the lever 67 being midway between the ends of the recess 69. In this last position, the sheet is gripped impositively,—

strongly enough to be moved by the gripper yet lightly enough to escape from the gripper jaws upon its edge coming into engagement with an abutment. If it is desired to modify the strength of the impositive gripping above referred to, this may be effected by manipulating the screw 67^b.

At its end opposite to that which carries the jaws 65 and 66, and beyond the central portion 60, the feed-gripper is formed with a pair of arms 71, in the ends of which are revolvably mounted bushings 72 having square holes therein. Extending through the square holes of the bushings 72 in the arm 71 of the feed-grippers is a rock-shaft 73 of square cross-section for a portion of its length. Upon this rock-shaft are mounted arms 74 having square holes therein, so that they rock with the shaft. These arms 74 are located between the arms 71 of the feed-grippers, and engage at their ends in the notches 68 of the jaw-actuating levers 67; so that the rocking of the shaft 73 will effect the several movements of the levers 67. Both the arms 74 and the bushings 72 of the feed-grippers can slide lengthwise of the rock shaft 73, which enables the feed-grippers, carrying with them the arms 74, to be adjusted lengthwise of the gripper-bar 58 as units.

Near its end adjacent the feed arm 48, the rock-shaft 73 has loosely mounted on it an arm 75, the opposite end of which is feathered upon an extension 76, of reduced diameter, formed on the end of the gripper-bar 58. To retain the arm 75 on the shaft-extension 76, a block 77 (Figure 6) is secured upon the feed arm 48 and formed with a shoulder which engages a corresponding shoulder on the arm 75.

A link 78 is connected to the rock-shaft 73 and extends downward lengthwise of the feed arm 48. At its lower end, this link enters a guideway on the feed arm and is provided with a cam-roll 79. The cam-roll travels in a cam-slot formed in a floating cam 80 pivoted at 81 to the left-hand side casting 20. As the feed arm swings to and fro the link 78 causes the feed-grippers 59 and the gripper-bar 58 to rock in such a manner that the fixed jaws 66 of the feed-grippers will follow a certain path with respect to the press platen *g*. The front part of the cam-slot is so shaped that the jaws 66, during the last part of their forward movement toward the stock pile and the first part of their return movement, will follow a path in which they clear the path followed by the front edge of the platen *g* as the latter rocks to and from its stationary sheet receiving position. The rear part 83 of the cam-slot is shaped so that the jaw 66 of the feed-grippers can follow a path parallel with the face of the platen, and in close proximity thereto, from a point near the center of the platen to a point close to the rear edge of the same.

5 A shaft 84 extends across the machine and has bearings in the side castings 20 and 21. At one end, this shaft has secured to it an arm 85 which is connected by an adjustable link 86 with a lug extending downward from the floating cam 80. At its other end, the shaft 84 is provided with a cam-arm 87 carrying a roll which engages the edge of a cam 30. The said edge is of such configuration 10 as to cause a drop of the cam-arm 87 when the feed-arm 48 and feed grippers 59 reach the end of their feeding movement. When this drop of the cam-arm 87 takes place, the shaft 84 rocks, and its arm 85, through the link 86, effects a depression of the floating cam 80. This, through the link 78, causes a slight raising movement of the front ends of the feed-grippers, enabling the jaws 66 of the latter, in their return movement, to clear 15 the sheet just fed.

20 Secured to the end of the rock-shaft 73 is an arm 88 to which is pivoted a link 89, the pivot being located substantially on the axis of the feed-bar 58. The link 89 extends down 25 beside the link 78 and is connected, by a pin 90 with an arm 97 pivoted to the feed arm 48. Upon the pin 90 is mounted a cam-roll 91, which, at one stage of the cycle of the machine, is adapted to engage beneath a cam-flange 92 which extends inwardly from the floating cam 80. The cam-flange 92 is so located that it will be engaged by, and remain in engagement with, the roll 91 at and for substantially the same time as the rear part 30 of the cam-slot is engaged by, and remains in engagement with the roll 79. A torsion spring 93 is connected between the arm 75 and a collar secured on the rock shaft 73, and tends to rock the shaft 73 in a clockwise direction, i. e. in a direction in which the arms 35 74 and actuating levers 67 hold the gripper jaws 65 firmly closed.

40 As the feed-arm 48 swings towards the platen *g* the cam roll 91 is not at first engaged by anything; consequently the gripper jaws 65 are held firmly closed by the action of the spring 93. When however, near the center of the platen, the feed grippers come close to the platen and begin to move parallel 45 therewith—which is the time the roll 79 enters upon the rear part 83 of its cam slot—the roll 91 will engage beneath the cam-flange 92, and will thereby be depressed. This depression of the roll 91 and link 89 causes the shaft 73 to rock, against the action of the spring 93, to a sufficient extent to raise the ends of the actuating levers 67 to a position 50 midway in the recesses 69 of the movable gripper jaws 65. When this occurs, the movable jaws 65 will engage upon the fixed jaws 66 by pressure of the leaf springs 67^a only, as has been described above.

55 Pivoted on the pin 90 which carries the cam roll 91, and resting against a lug 94 on the link 89, is a finger 95 connected by a ten-

sion spring 96 with a lug formed on the hub of the arm 97. Formed on the upper part of the floating cam 80, towards the front of the latter, is a cam-lug 98, the lower face of which is inclined downwardly and forwardly. When the feed-arm 48 swings forward to a position where the feed-gripper jaws are approaching the sheet held suspended from the separator feet 41, the finger 95, the top of which is inclined, engages beneath the cam-lug 98 and is forced downward, carrying with it the link 89. By this means the feed-gripper jaws are fully opened. Just as the feed arm completes its forward movement, the finger 95 passes beyond the cam-lug 98, whereupon the feed gripper jaws close under the action of the spring 93, thus seizing the sheet.

55 Formed in the feed arm 48 immediately below the gripper bar 58, is a passage for slidably receiving a plunger 99 from which a pin 100 extends upwardly and enters a slot 101 formed in the gripper bar 58 (Figs. 6 and 7). The under face of the bearing 57 is flattened, and has pivoted thereto, at 102, a cam lever 103 which is connected by a link 104 with the plunger 99, and is provided on its under side with a cam roll 105. The left-hand side casting 20 is formed with a rearward extension having at its end a guideway 106 formed with a longitudinal slot 107. In this guideway a block 108 is adjustably mounted by means of a bolt 109 passing through the slot 107. The block 108 is formed with a cam-slot 110 for receiving a cam-roll 105 at the end of the rearward feeding swing of the feed-arm 48. The cam-slot 110 is flared outwardly at its front end, to provide an easy entrance for the roll, and is inclined to the left at its rear end. When the roll 105 enters the rear part of the cam-slot, therefore, it will be forced to the left, and this, through the cam-lever 103, link 104, plunger 99 and pin 100, will cause the gripper bar 58 to slide lengthwise in the bearing 57 a short distance to the left. It is this sliding movement of the gripper bar which effects the side-registering of the sheet on the platen *g*. If it is desired to register to the right instead of the left, it is merely necessary to remove the block 108 and replace it the other side up. By loosening the bolt 109, the position of the block 108 can be adjusted to accord with the adjustment of the throw of the feed arm by means of the pin 52 in the curved slot 50.

115 The operation of the feeding device described here is as follows: Supposing that, so far as presswork is concerned, the press has been made ready for printing, the end-register gage pins *h*, *h* and the side register pin *i* will have been placed in the proper positions on the platen. To adjust the throw of the feed-arm 48 (supposing sheets of a different length have been previously fed) the 120 125 130

press is turned over until the bed *e* is in its rearmost, open position, with the pins of the crank-arms *d* on their dead centers. The nut 51 is then loosened and the feed arm 48 moved forward or back (the pin 52 sliding in the curved slot 50) until the jaws 66 of the feed grippers 59 are a very slight distance to the rear of the line which the edge of the paper will occupy when it is in engagement with the 10 end-register pins *h* (Fig. 5). The block 108 is then adjusted so that the roll 105 will nearly reach the extremity of its slot 110 when the feed arm completes its rearward movement. The pile of stock is placed in the 15 proper position with respect to the location of the side register pin *i* on the platen, and the feed grippers 59 and separator feet 41 are appropriately adjusted on their bars 58 and 33, with respect to each other and with respect to the end-register pins *h*, *h* on the platen. The machine can then be set in motion.

As the feed arm 48 swings forward towards the pile after the roll 91 has left the cam-flange 92, the jaws of the feed grippers are closed; but as soon as the finger 95 strikes the cam-lug 98 they will begin to open. By this time the separator feet 41 will have raised a sheet into position to be embraced by the 25 jaws of the feed-grippers. As the feed-arm completes its forward movement, the finger 95 passes beyond the cam-lug 98 and the jaws of the feed-grippers snap shut upon the sheet. A valve is then actuated to cut-off the suction and release the sheet from the separator feet 41. Thereupon the feed arm 48 begins 30 to swing rearward, the feed grippers carrying with them the sheet towards the platen *g*, which latter is rocking towards its open position. During the first part of this rearward movement the ends of the feed grippers are considerably above the platen, to allow room for the front edge of the latter to rock past. When, however, the cam-roll 79 reaches the 35 front end of the rear part 83 of the cam-slot, the jaws 66 of the feed grippers will have come into close proximity with the platen, and thereafter will travel parallel therewith. At the same time, the roll 91 will have come 40 into engagement beneath the cam-flange 92, whereby the gripper jaws 65 will be relieved from the action of the spring 93 and will engage upon the sheet by the action of the leaf springs 67^a alone, thereby retaining the sheet 45 impositively. Just before the feed arm concludes its rearward movement, the front edge of the sheet strikes the end-register pins *h*, *h*. The feed grippers then proceed onward, slipping off the impositively held sheet; but before they leave the sheet they move laterally 50 of the platen, due to the engagement of the roll 105 in the cam-slot 110 of the block 108, thereby moving the sheet into engagement with the side register pin *i*. After this, the 55 feed arm moves just the slight distance fur-

ther necessary to carry the feed gripper jaws clear of the sheet. As the rearward movement of the feed arm 48 is thus completed, the cam causes the shaft 84 to rock slightly, whereby the link 86 swings the floating cam 70 80 slightly downward. This, through the cam-roll 79 and link 78, causes an upward tilting of the ends of the feed-grippers, allowing them to clear the newly-fed sheet in their return movement. 75

Having thus fully described my invention what I claim as new and desire to secure by Letters Patent is:

1. A sheet register apparatus for platen presses comprising a device for holding a sheet impositively, means for moving said device forwardly across the platen to feed a sheet to the latter, and means for moving said device laterally to register the sheet sidewise. 80

2. A sheet register apparatus for platen presses comprising a device for holding a sheet impositively, means for moving said device forwardly across the platen to feed a sheet to the latter, and means for moving said device laterally, substantially at the extremity 90 of the forward movement, to register the sheet sidewise. 95

3. A sheet register apparatus for platen presses comprising a device for holding a sheet impositively, means for moving said device forwardly across the platen to feed a sheet to the latter, means for adjusting the extent of said forward movement, and means for moving said device laterally, substantially at the extremity of the forward movement, 100 for registering the sheet sidewise. 105

4. The combination with a platen press having an end stop and a side stop thereon, of a device for holding a sheet impositively, means for moving said device forward over the platen to feed a sheet to the latter and bring said sheet into engagement with said end stop, and means for moving said device laterally, substantially at the extremity of 110 the forward movement, to register the sheet against said side stop. 115

5. The combination with a platen having a front stop and a side stop thereon, of a device for holding a sheet impositively, means for moving said device forwardly over the platen to deposit a sheet against said end stop, means for adjusting the extent of movement of said device to accord with the position of said end stop, and means for moving said device laterally, substantially at the extremity of the forward movement, to register the device against said side stop. 120

6. The combination with a platen having a front stop and a side stop thereon, of means for holding a sheet impositively, means for moving said device forward over the platen, part of said forward movement being close to the platen, means for adjusting the extent of movement of said device, 125 130

and means for moving said device laterally, substantially at the extremity of the forward movement, to register the sheet sidewise.

7. The combination with a platen, of a movably mounted support, means for moving said support forwardly and rearwardly with respect to the platen, a member extending transversely with respect to the platen and movably associated with said support, a gripper carried by said member and constructed to hold a sheet impositively, and means for moving said member transversely of the platen.

8. The combination with a platen having an end stop and a side stop thereon, of a movably mounted support, a member movably associated with said support and disposed to extend transversely of the platen, a gripper carried by said member and constructed to hold a sheet impositively, means for moving said support forwardly with respect to the platen whereby said gripper deposits the sheet against said end stop, and means for moving said member transversely with respect to the platen, substantially at the extremity of the forward movement of said support, whereby said gripper registers the sheet against said side stop.

9. In a method of feeding sheets to a platen printing press, the steps which consist in transferring successive sheets from the stack to the platen by a predetermined path, imparting to such sheet a shifting movement transversely of its path of travel as it approaches the platen, and simultaneously releasing the sheet whereby it may be brought accurately to rest against both the forward and lateral stop pins on said platen.

10. In a method of feeding sheets to a platen printing press, the steps which consist in transferring successive sheets in an approximately arcuate path from the stack to the platen, imparting to such sheet a shifting movement transversely of its path of travel as it approaches the platen, and simultaneously releasing the sheet whereby it may be brought accurately to rest against both the forward and lateral stop pins on such platen.

EDWARD CHESHIRE.
